UNITED STATES PATENT OFFICE.

ALFRED T. NEWELL, OF BIRMINGHAM, ALABAMA.

CULVERT AND ARCH CONSTRUCTION.

Application filed December 16, 1921. Serial No. 522,805.

To all whom it may concern:

Be it known that I, ALFRED T. NEWELL, a citizen of the United States, residing at Birmingham, in the county of Jefferson and State of Alabama, have invented certain new and useful Improvements in Culvert and Arch Constructions, of which the following is a specification.

The object of the present invention is to provide improved means for producing a concrete structure such as a culvert, arch, pier or the like, and embodying the conception of such a structure produced by means of pre-formed concrete slabs, which may be cast in a central plant, shipped to the place of use, and quickly set up. It will be found particularly useful in road, arch and bridge work, the units being such that culverts or arches or piers of various sizes and shapes may be constructed in segmental units pre-formed as stated. These units will be reinforced by metal rods or wires embedded therein, and the reinforcements are utilized for the purpose of bonding the slabs in the position where they are to remain. Various forms of the invention are possible, and a few are illustrated in the accompanying drawings in which Fig. 1 is an end view of a culvert made of slabs embodying the invention. Fig. 2 is a top view thereof. Fig. 3 is an end view of a modified form. Fig. 4 is a top view of Fig. 3. Fig. 5 is an end view of another form. Fig. 6 is an end view of an arch. Fig. 7 is a side elevation of a pier. Fig. 8 is a section on the line 8—8 of Fig. 7. Fig. 9 is a perspective of one of the slabs.

The forms shown in Figs. 1 to 5 may all be produced from the same units. Each unit consists of a slab 6, the ends and side edges of which are rabbeted as indicated at 7, the rabbets being of the same depth and width, and being one-half as wide as the total thickness of the slabs. This permits the slabs to be fitted together in various arrangements. The slabs are also preferably twice as long as they are wide.

At each corner the slabs are rabbeted or recessed as indicated at 9, and they are also recessed at the middle, as shown at 10, on each side, the recesses 10 being twice as wide as the recesses 9. Any suitable number of reinforcing rods may be embedded in the slabs, and particularly one of the reinforcing rods 55 extends around the outer edge of each slab, in such position that it will be exposed in

the recesses 9 and 10, as shown at 11, thereby forming loops or portions to which ties can be attached, for the purpose of fixing the slabs together.

In producing a simple form of culvert, as shown in Fig. 1, four of these slabs are fitted together at the corners, the rabbeted portions of each interfitting with each other, and when this is done the corner and intermediate recesses 10 will register with each other, at the middle and the corners of the respective slabs. Then the slabs are tied together by means of wire ties 12 which are looped around the loops or portions 11 of the reinforcing rods, so that all four slabs are tied together at the middle and also at the corners. Mortar may be used in the joints if desired, but as they are nicely fitted it will be unnecessary in ordinary culvert work. The length of the culvert may be extended by adding sections to each other endwise, these sections being abutted at the ends of the slabs and also tied together by ties between the loops 11 at the end corners as shown in Fig. 2. In the form shown in Figs. 1 and 2 the resulting culvert will be of a size corresponding to the width of the slabs.

For producing a wider culvert the slabs may be set up as shown in Figs. 3 and 4. That is, the side slabs extend lengthwise horizontally, but the top and bottom slabs extend crosswise, two top and bottom slabs being joined to a single slab at each side of the culvert. This requires the same number of side slabs as shown in Figs. 1 and 2, but double the number of top and bottom slabs. And in this form, also the recesses 9 and 10 register with each other where the slabs meet, and the loops 11 are connected by ties 12 twisted around the same. In Fig. 5 a tall narrow culvert is illustrated, the side slabs standing on their ends and being connected to top and bottom slabs of single width.

The invention is capable of extension to arches, as shown in Fig. 6. In this construction the top slabs 26 are made segmental in form and may be assembled with the flat slabs above described, the segmental slabs being also provided with corner and middle recesses and exposed loops or reinforcements 11 at the corners and the middle, whereby the arch slabs may be tied together and to the side walls of the arch in the same manner as above described.

For piers and such vertical work, the arch

slabs can be set together with their convex faces outwardly, as shown in Figs. 7 and 8, and when so set united by ties as described. The hollow structure then formed can be 5 filled with rock or concrete to make a solid pier. By varying the curvature of the segmental sections piers of various shapes and dimensions can be formed. Thus a round pier can be made by using four of the segmental sections shown in Fig. 8, each section forming a quarter of the circumference.

By the use of pre-formed slabs in the manner described the cost and labor of building forms for the production of concrete culverts and bridges is avoided, and 15 the culvert is completed when the slabs are set together and does not have to wait to cure. Traffic can go over it at once, thus avoiding delays and detours incident to concrete bridge construction, which frequently 20 takes several weeks time before all parts of a bridge arch can be cast in place. The square slabs for ordinary culverts can be produced in large quantities at a central

plant and shipped to the place where they 25 are to be used, and since they are made uniform, will fit each other to produce various forms and sizes.

I claim:

1. A pre-formed concrete slab for culvert 30 and arch construction or the like, the length of said slab being twice its width, the edges of said slab being rabbeted to interlock with adjacent slabs, and the corners of said slab having recesses and reinforcing rods exposed in said recesses to receive ties to fasten adjacent slabs together.

2. A pre-formed concrete slab suitable for 35 culvert and arch construction or the like, said slab having a rabbet extending entirely 40 around its edge, the depth of the rabbet being half the thickness of the slab, and the edges of the slab being provided with recesses and with reinforcing rods exposed at 45 said recesses.

In testimony whereof I affix my signature.

ALFRED T. NEWELL.
